(57) **CLAIM**

The ornamental design for a wind chime, as shown and described.

DESCRIPTION

FIG. 1 is a front elevation view;
FIG. 2 is a back elevation view;
FIG. 3 is a right side view; the left side view being a mirror image thereof;
FIG. 4 is a top plan view; and,
FIG. 5 is a bottom plan view.
In the drawings, the broken lines depict environmental subject matter only and forms no part of the claimed design.
